UNITED STATES PATENT OFFICE.

MYERS A. GARRETT, OF CHICAGO, ILLINOIS

DRAFT AND BUFFING GEAR FOR CARS.

No. 926,110.

Specification of Letters Patent.

Patented June 29, 1909.

Application filed March 7, 1908. Serial No. 419,788.

To all whom it may concern:

Be it known that I, MYERS A. GARRETT, a citizen of the United States, residing at Chicago, in the county of Cook and State of Illinois, have invented new and useful Improvements in Draft and Buffing Gear for Cars, of which the following is a specification.

The object of my invention is the provision of a gear for taking and absorbing the strains and shocks incident to buffing and towing mainly through the medium of frictional surfaces or elements movable one upon another, and which preferably shall be supplemented by a cushioning device or devices for taking the initial strains.

The invention consists in certain novelties of construction and combinations of parts as hereinafter set forth and claimed.

The accompanying drawing illustrates an example of the physical embodiment of the invention constructed according to the best mode I have so far devised for the practical application of the principle.

Figure 1 is a top plan of the gear. Fig. 2 is a section taken in a vertical plane on the line $\alpha-\alpha$, Fig. 1. Fig. 3 is a plan of one of the cheek plates and shows the relative arrangement and location of the slots in the draft sills or supports, and the cheek plates. Fig. 4 is a plan of one of the draft links. Fig. 5 is a horizontal section of Fig. 2 taken on a plane substantially coinciding with the draw bar, keys and slots in the central stringers.

Referring to the figures, the numeral 1 designates an end sill of a car floor frame; 2, the center sills or stringers, in this instance of channel beams, though they may be of other shape in cross section; 3, cheek plates secured by rivets to the webs of the channel beams; 4, a front slot in the web of each channel beam and cheek plate $8\frac{1}{2}$ " in length; 5, a second slot $4\frac{1}{2}$ " in length; 6, a third slot $3\frac{1}{2}$ " in length; 7, a fourth slot $4\frac{1}{2}$ " in length; 8, a draw bar of any approved type; 9, a slot in the draw bar; 10, the draft links; 11, 12, 13, 14, slots in the draft links, all but 14 elongated; 15, a metallic compression block with a lug seated within the end of the draw bar; 16, a hole therethrough; 17, a recess at one end of the block and within the body thereof; 18, an upper inclined frictional surface; 19, a lower inclined frictional surface; 20, pincers; 21, the lever ends or handles; 22, curved frictional

surfaces which engage the surface, 18 and 19 bounding the recess in the compression block; 23, the jaws of the pincers; 24, recesses in the jaws; 25, a spring or springs or cushion between the jaws; 26, holes for a fulcrum pin; 27, the fulcrum pin passed through the holes and with its ends located within the slots in the links and sills or supports; 28, the frictional surfaces at the ends of the jaws; 29, a friction plate; 30, a boss upon the face of the plate; 31, friction surfaces at the end of the pincers jaws; 32, lugs for supporting springs; 33, two sets of helical springs; 34, a follower block; 35, lugs supporting the helical springs; 36, a hole through the block; 37, a key passed through the block and also through the slots in the links and sills; 38, a filler block riveted to the sills and against which the follower block rests in buffing; 39, a key passed through the slot in the draw bar and its ends located within the slots of the links and sills or supports; and 40 is a key passed through the hole in the compression block and its ends located and supported within the slots in the links and sills or stringers.

In practice the main parts of the gear may be applied in connection with the so-called draft timbers or sills of a car, all the keys to be flat instead of round, and a spring or cushion 41 to be used between the lever ends.

The several parts and elements of the combined device being in the relative positions shown by the drawings, the mode of operation is as follows: In towing the draw bar is advanced, carrying with it the links which slide over the key 40 and fulcrum pin 27, and the follower block and key 37. As the draw bar is further advanced the cushions 23 are compressed, and the friction plate 29 is forced against the pincers jaws relative to which they move in frictional contact and compress spring 25 as they turn in closing about the fulcrum pin. The lever ends of the pincers simultaneously approach each other and their frictional surfaces travel downwardly upon the inclined surfaces bounding the recess in the compression block. In buffing the follower block is stationary and the draw bar, its key, the compression block, the pincers, and the friction plate are forced rearwardly against the cushion 38, the links remaining stationary by reason of the presence therein of the elongated slots. When the cushion 38 is present the arrangement is such that the

fulcrum pin can move about $\frac{1}{4}$ " rearwardly, compressing the cushion and absorbing light shocks before the pincers commence to turn about the fulcrum pin, then the lever ends and the jaws commence to travel relative to the frictional surfaces with which they are in contact and at the same time compress spring 25. The operation is the same when the cushion 33 is omitted and the plate and follower block are in contact, except that the pincers immediately commence to turn about the fulcrum pin and compress the spring or cushion 25 and the lever ends and jaws travel relative to the frictional surfaces with which they are in contact. Obviously, the degree of pressure between the frictional surfaces may be regulated by the use of springs or cushions 25 of unequal resistance to compression.

20. What I claim is:

1. The combination in a draft and buffing gear, of a draw bar; a compression block; pincers; a cushion between the jaws of the pincers; a follower block located in the rear of the pincers; means for retaining the several elements in their relative positions; and means for transferring motion from the draw bar to the follower block in drawing.

2. The combination in a draft and buffing gear, of a draw bar; a compression block; pincers; a cushion in connection with the pincers; a follower block; means for retaining the several elements in their relative positions; and links for transferring motion from the draw bar to the follower block in drawing.

3. The combination in a draft and buffing gear, of a draw bar; a compression block; pincers; a cushion in connection with the pincers; a follower block; keys and a fulcrum pin for retaining the several elements in their relative positions; and means for transferring motion from the draw bar to the follower block in drawing.

4. The combination in a draft and buffing gear, of a draw bar; a compression block; pincers with a movable fulcrum; a cushion in connection with the pincers; a friction plate; a follower block; a cushion between the plate and follower block; means for retaining the several elements in their relative positions; and means for transferring motion from the draw bar to the follower block in drawing.

5. The combination in a draft and buffing gear, of a draw bar; a compression block; pincers with a movable fulcrum; a cushion in connection with the pincers; a friction plate; a follower block; a cushion between the plate and follower block; keys for retaining the several elements in their relative positions; and means for transferring motion from the draw bar to the follower block in drawing.

6. The combination in a draft and buffing

gear, of a draw bar; a compression block; pincers with a movable fulcrum; a cushion in connection with the pincers; a friction plate; a follower block; a cushion between the plate and follower block; means for retaining the several elements in their relative positions; and links for transferring motion from the draw bar to the follower block in drawing.

7. The combination in a draft and buffing gear, of a draw bar; a compression block; pincers with a movable fulcrum; a cushion in connection with the pincers; a friction plate; a follower block; a cushion between the plate and follower block; keys for retaining the several elements in their relative positions; and links with elongated slots for transferring motion from the draw bar to the follower block in drawing.

8. The combination in a draft and buffing gear, of a draw bar; a compression block; pincers with a movable fulcrum; a cushion between the jaws of the pincers; a friction plate; a follower block; a cushion between the plate and follower block; a filter block against which the follower block bears in buffing; means for retaining the several elements in their relative positions; and means for transferring motion from the draw bar to the follower block in drawing.

9. The combination in a draft and buffing gear, of sills or supports with slots; a draw bar; a compression block; pincers with a fulcrum; a cushion in connection with the pincers; a follower block; slotted links; and keys passed through the slots in the draw bar, compression block, follower block, and sills or supports.

10. The combination in a draft and buffing gear, of sills or supports with slots; a draw bar; a compression block; pincers with a fulcrum; a cushion in connection with the pincers; a follower block; a friction plate; a cushion between the plate and follower block; slotted links; and keys passed through the slots in the draw bar, compression block, follower block, and sills or supports.

11. The combination in a draft and buffing gear, of supports; a draw bar; pincers having a common fulcrum and located between the draft sills and in line with the draw bar; and means in connection with the draw bar for operating the pincers when the draw bar is moved in drawing and buffing.

12. The combination in a draft and buffing gear, of pincers having a common fulcrum lever ends and jaws, and a cushion between the jaws.

13. The combination in a draft and buffing gear, of pincers with lever ends and jaws, an element with frictional surfaces in connection with said lever ends, a cushion in connection with the jaws, and an element with a frictional surface in connection with the jaws.

14. The combination in a draft and buffing gear, of pincers, elements with frictional surfaces at both ends of the pincers, a cushion in connection with the pincers, a follower block, and a cushion between the follower block and the frictional element at one end of the pincers. 5
15. The combination in a draft and buffing gear, of a compression block, pincers with a movable fulcrum; a cushion in connection with the pincers; and a friction plate or element at the end of the pincers. 10
16. The combination in a draft and buffing gear, of a compression block, pincers with a fulcrum pin movable with the pincers, a cushion between the jaws of the pincers, a friction plate, a follower block, and a cushion between the follower block and friction plate. 15
- 20 17. The combination in a draft and buffing gear, of a compression block with a recess having inclined surfaces, pincers with lever ends and jaws, a cushion in connection with the jaws, and a friction plate in contact with the jaws. 25
18. The combination in a draft and buffing gear, of supports with slots, pincers with a fulcrum pin having its ends located in the slots, a cushion in connection with the pincers, and frictional elements at the ends of the pincers. 30
19. The combination in a draft and buff- 35
- ing gear, of supports with slots, pincers with a movable fulcrum pin having its ends located in the slots, a cushion in connection with the pincers, and frictional elements at the ends of the pincers. 40
20. The combination in a draft and buffing gear, of supports with slots, a compression block, pincers, a cushion in connection with the pincers, a friction plate, a follower block, a cushion between the follower block and plate, keys passed through the follower block and compression block and movable in the supports, and a movable fulcrum pin 45 for the pincers with its ends movable within the slots of the supports.
21. The combination in a draft gear, of pincers having a common fulcrum and lever ends with a cushion between them. 50
22. The combination in a draft gear, of pincers having a common fulcrum, lever ends and jaws, and a cushion between the jaws. 55
23. The combination in a draft gear, of pincers having lever ends and jaws and a cushion between the lever ends and also between the jaws.

In testimony whereof I affix my signature in presence of two witnesses.
